UNITED STATES PATENT OFFICE.

GEORGE S. JONES, OF LOS ANGELES, CALIFORNIA.

DESIGN FOR A CABINET.

Application filed June 1, 1925. Serial No. 13,622. Term of patent 14 years.

To all whom it may concern:

Be it known that I, GEORGE S. JONES, citizen of the United States, residing at Los Angeles, county of Los Angeles, and State of California, have invented a new, original, and ornamental Design for Cabinet, of which the following is a specification, reference being had to the accompanying drawing, forming a part thereof.

Fig. 1 is a view of the cabinet as seen in front elevation;

Fig. 2 is an end view of same;

Fig. 3 is a perspective view.

I claim:—

The ornamental design for a cabinet substantially as shown.

GEO. S. JONES.
